(57) **CLAIM**

The ornamental design for a lamp, as shown and described.

DESCRIPTION

FIG. 1 is a perspective view of a lamp showing my new design where the lamp is in a first configuration of use; FIG. 2 is a perspective view of the lamp where the lamp is in a second configuration of use; FIG. 3 is a perspective view of the lamp where the lamp is in a third configuration of use; FIG. 4 is another perspective view of the lamp where the lamp is in the first configuration of use; FIG. 5 is a front elevational view thereof; FIG. 6 is a rear elevational view thereof; FIG. 7 is a left side elevational view thereof; FIG. 8 is a right side elevational view thereof; FIG. 9 is a top plan view thereof; and, FIG. 10 is a bottom plan view thereof. The broken lines in the drawings depict portions of the lamp that form no part of the claimed design.
